UNITED STATES PATENT OFFICE.

CHRIS F. DOWNEY, OF WATERBURY, CONNECTICUT.

DESIGN FOR A CLIP FOR COFFEE-POT STRAINERS.

SPECIFICATION forming part of Design No. 27,594, dated August 31, 1897.

Application filed July 13, 1897. Serial No. 644,451. Term of patent 14 years.

To all whom it may concern:

Be it known that I, CHRIS F. DOWNEY, of Waterbury, in the county of New Haven and State of Connecticut, have invented a new 5 Design for Wire Clips for Strainers for Coffee-Pots, &c.; and I do hereby declare the following, when taken in connection with the accompanying drawings and the letters of reference marked thereon, to be a full, clear, 10 and exact description of the same, and which said drawings constitute part of this specification, and represent, in—

Figure 1, a perspective view of a clip embodying my design and indicated as attached 15 to a strainer; Fig. 2, a plan view of the clip.

This invention relates to a design for wire clips for strainers for coffee-pots or other vessels; and it consists in the configuration as

hereinafter described, and shown in the accompanying illustrations.

The clip comprises two short ends *a a*, forwardly-projecting loops *b b*, and a reversely-turned curved tongue *c*, all as shown in the accompanying illustrations.

I claim—

The design for a wire clip for strainers for coffee-pots &c., substantially as shown and described.

In testimony whereof I have signed this specification in the presence of two subscribing witnesses.

CHRIS F. DOWNEY.
